UNITED STATES PATENT OFFICE

SAMUEL RUBEN, OF NEW YORK, N. Y., ASSIGNOR TO RUBEN PATENTS COMPANY, OF NEW YORK, N. Y., A CORPORATION OF DELAWARE

IONIC-DISCHARGE DEVICE

Application filed April 4, 1927. Serial No. 180,989.

This invention relates to an electrical discharge device, and more particularly it relates to a relay for the control of currents of densities comparatively high in respect to 5 those controlling the local circuits therein.

The object of the invention is to provide a device for controlling by minor potential variations the current discharges of relatively high densities in an external circuit which 10 may be opened and closed at very high rates of speed.

The device of the present invention is an improvement as to speed of operation, upon that described in my prior and copending 15 patent application, Serial No. 418,896, filed October 23, 1920, and refiled October 10, 1926, by which the current discharge through an external circuit is controlled by the movement of its anode plate in response to the 20 kinetic energy of its electronic bombardment by the electron stream from the cathode, the electronic bombardment having a direct mechanical effect upon the position of one end of the anode plate, by the movement of which, 25 the external circuit is opened and closed. The mechanical force thereby obtained is, however, of such small magnitude that the pressure responsive element must be very light and delicate.

30 By the employment of an ionic discharge instead of an electronic discharge, due to the large mass of the ion compared with that of the electron, much greater force or pressure is obtained, with greater response by the bombarded element which can, therefore, be less sensitive and delicate. As the bombarding ion, I prefer that of neon gas and caesium vapor, because of the low discharge potential of the former and the large amount of kinetic 35 energy available from the ionic discharge of the latter for the operation of the pressure-sensitive cathode element. The neon gas is used in starting the discharge because the caesium has insufficient vapor pressure there- 40 for at normal room temperature; but, after starting, the heat radiated from the electrode and conducted by the low pressure gas atmosphere increases the caesium vapor pressure so that it then becomes the conductive 45 element, with its greater mass bombardment

effect upon the movement of the flexible cathode element.

In a preferred form of device the caesium is applied in a compound mixture of powdered caesium chloride and magnesium powder compressed and heated inductively within the tube to the reaction temperature, when the magnesium vapor is released, absorbing all of the occluded surface and residual chemically active gases, and reducing the caesium 55 chloride to caesium metal, which is deposited by condensation on the inner walls of the containing vessel or tube. The residue of magnesium chloride remains within the original containing metal walled element. 60

The invention therefore involves broadly, the use of a low pressure gas-filled tube adapted for the application of a vapor pressure, and having a light weight cathode element delicately responsive to ionic impact 70 from ionic discharges of the vapor pressure between the anode and cathode, the movement of one end of the latter serving to actuate a current-making-and-breaking device within the tube and in an external circuit to be 75 controlled or affected. The gas within the tube employed for the conduction of the initial ionic discharge is preferably a monoatomic gas; but for more effective operation, after sufficient heat is generated within the 80 tube, a vapor pressure, preferably that of caesium, or potassium, etc., is employed.

The principles of the invention can best be further explained in connection with a certain illustrative embodiment thereof, shown 85 in the accompanying drawings, in which Figs. 1 and 2 diagrammatically show two views of the ionic bombardment relay device, and Figs. 3 and 4 show in greater detail several of its elements.

Referring more particularly to Figs. 1 and 2, C represents a glass tube or envelope, first evacuated and deprived of occluded gases as far as practicable, and into which neon gas has then been admitted at low pressure; the tube 95 is mounted on base 1. Within the tube is cathode plate 2, consisting of a thin molybdenum diaphragm mounted on a conducting wire 5, and a control element 9, forming a ring 9a about the end of the anode, and mount- 10

ed on a conducting wire having a terminal at 9_b. Mounted on the end of cathode supporting wire 5, is tungsten contact point 5_a, opposite fixed tungsten contact point 6_a, on conducting wire 6, of the external circuit to be operated by the opening and closing of gap 5_a—6_a, cathode 2 being also connected in that circuit.

Anode 7 is partially electrically shielded 10 by glass tube 8. At 10, mounted on rod 10, projecting from the glass stem, is a vessel containing a powdered mixture of magnesium and caesium chloride; in its metal wall is a small orifice 10_a for the escape of vapor when 15 that vessel is heated by the ionic discharge. At 7_a, 5_b and 6_b are respectively the terminals of anode 7, cathode 2 and conducting wire 6 of the external circuit, in which cathode 2 is also connected.

20 Figs. 3 and 4 illustrate respectively in more detail the grid or control circuit element or ring 9, encircling the end of anode wire 7, and the nickel walled vessel 10 containing the material from which the vapor pressure is derived. For higher speed operation the cathode plate is extended to opposite the fixed contact point and the movable tungsten contact is omitted, the fixed contact being then a small tungsten wire contact point.

25 In operation, as a potential is established between the cathode and anode, the neon gas becomes conductive and, with the discharge between those electrodes, the radiated heat and that conducted by the electrodes raises 30 the temperature of the caesium metal to the point of vaporization. The conductive capacity of the gap is increased with the increase of the vapor pressure and a more intense ionic bombardment of the cathode occurs, forcing the upper end of that element over until its contact point closes the gap of the external circuit. The impression of a negative potential upon the control circuit varies and decreases the ionic bombardment 40 of the cathode and the gap is again open, the current discharge through the external circuit ceasing. The cycle of opening and closing the external circuit continues with the intermittent reception of radio signals impressed upon the control circuit. In this 45 way very high speed of operation of the circuit opening and closing device is obtained.

What I claim is:

50 1. A relay device comprising an evacuated tube having therewithin a metal vapor and a gas at low pressure, a control element, an anode and a vibratory diaphragm constituting a cathode and having a contact, and a contact member adapted to be engaged by the 55 cathode contact on movement of the diaphragm in response to ionic bombardment thereof.

60 2. The combination with an evacuated tube having a metal vapor and a gas at low pressure, of a control element, an anode and a co-

65 operating cathode element separated from the anode by a gap, the cathode consisting of a vibratory diaphragm flexibly responsive to the impact of ionic discharge from the anode and a contact member adapted to open and close an external circuit, responsive to variations of the ionic bombardment of the cathode in response to potential variations of the control element.

70 Signed at the city of New York, in the county of New York and State of New York this 2nd day of April A. D. 1927.
